UNITED STATES PATENT OFFICE.

CISCO R. TRAXLER AND EDWARD E. LINEBACK, OF WINSTON SALEM, NORTH CAROLINA.

TROLLEY-POLE CONTROLLER.

No. 881,359.

Specification of Letters Patent. Patented March 10, 1908.

Application filed April 16, 1907. Serial No. 368,512.

To all whom it may concern:

Be it known that we, CISCO R. TRAXLER and EDWARD E. LINEBACK, citizens of the United States, residing at Winston Salem, 5 in the county of Forsyth and State of North Carolina, have invented certain new and useful Improvements in Trolley-Pole Controllers; and we do declare the following to be a full, clear, and exact description of the 10 invention, such as will enable others skilled in the art to which it appertains to make and use the same, reference being had to the accompanying drawings, and to the letters and figures of reference marked thereon, 15 which form a part of this specification.

Our invention relates to trolley pole controllers.

It has for its object to provide a device which in the event of the trolley jumping 20 the wire will retract the trolley and its pole below the plane of the cross wires and stays and other parts of the overhead structure to avoid damage thereto, and in which the retractor will be brought into play after the 25 trolley pole cord has been drawn taut so that the retracting power or force will be gradually applied thus avoiding sudden pulling or jerking on the cord which if permitted would tend to snap or break the cord; also 30 in which the construction may be composed of the minimum number of parts, simple in construction, inexpensive to construct and apply, efficient in action, and not liable to get out of working order.

35 To the accomplishment of the foregoing and such other objects as may hereinafter appear the invention comprises a weight attached to the trolley pole cord, a suitable guide for the weight in its vertical movements, and a seat for sustaining the weight 40 until bodily moved therefrom by tension on the trolley pole cord whereupon the weight may exert itself to retract the pole and its trolley below the plane of the trolley wire.

45 In its more specific form it comprises a tube having in its wall a longitudinally disposed slot with which communicates a laterally disposed slot, and a weight fitted in the tube and connected with the trolley pole 50 cord and provided with a laterally extending projection or pin which works in the longitudinally disposed slot of the tube and may be shifted into the laterally disposed slot and rest upon the bottom wall thereof which 55 will constitute a seat to hold the weight in its elevated position until moved therefrom

by tension on the trolley pole cord when the trolley leaves its wire whereupon the lateral pin or projection will be drawn into the longitudinally disposed slot so that the 60 weight may descend and pull down the trolley pole so as to carry the trolley below the plane of the trolley wire.

In the accompanying drawing Figure 1 is a side view of one end of a car showing our 65 controller applied thereto; Fig. 2 is a side view of the controller tube showing the weight elevated and seated, and Fig. 3 is a longitudinal section through the same showing the weight in its lowermost position. 70

In the drawing, the numeral 1 designates a car to the front and rear of which the controller will be applied, it being sufficient to illustrate it at one end as the construction will be the same at both ends. The trolley 75 pole 2 is of any approved type and under the control of a spring (not shown) as usual and carries a trolley 3 for the trolley wire 4 as usual. The controller, in the form illustrated, comprises a tube 5 of any desired 80 length and dimensions, and for purposes of illustration is shown as bolted to the projecting portion of the platform, outside of the dashboard. The tube is formed with a longitudinally disposed slot 8 between the ends of 85 which, at an appropriate point in the length, communicates a laterally disposed slot 9 which in the form illustrated is disposed obliquely to the longitudinal slot so as to form a secure seat for the weight presently 90 mentioned, thus preventing the weight from being accidentally displaced. The weight is designated by the numeral 10, which may be of any desired form in cross section but is shown as cylindrical. It is provided with a 95 lateral extension or projection 11 which is shown in the preferred form of an eye bolt, and which extends through the longitudinally disposed slot 8. This eye bolt serves for the attachment of the trolley pole cord 7 100 to the weight and also for seating the weight on the bottom wall of the laterally disposed slot 9 when the eyebolt is made to enter that slot, and it also enables the trolley pole cord to be outside of the tube so as to be within 105 easy access and control of the conductor of the car. While the cord may be attached directly to the eyebolt it is preferred to provide the cord with snap hooks 12 so that the cord can be readily detached when the pole 110 and cord are to be shifted from one end to the other of the car.

In the normal position of the weight it is in the upper portion of the tube or guide and its lateral pin is in the lateral slot the bottom wall of which constitutes a seat for the weight, 5 the obliquity of the slot preventing the weight from being unseated from any jarring motion of the car, or otherwise. If the trolley jumps the wire the spring of the trolley pole raises the latter which takes up slack in the 10 trolley pole cord and as the rope becomes taut in the further upward movement of the pole a sharp pull is exerted on the weight and it is raised so that its lateral pin or bolt moves from the lateral into the longitudinal 15 slot thereby bodily lifting and unseating the weight whereupon it descends in the tube or guide and by reason of it being heavier than the power of the trolley pole spring pulls down the trolley pole until the weight rests 20 at the bottom of the tube or guide. The weight being unseated at a time when the trolley cord is taut there is no sudden dropping of the weight when unseated, but it descends gradually and in opposition to the 25 resistance offered by the trolley pole spring, and consequently there is no liability of snapping or breaking the trolley cord by a sudden dropping of the weight before the cord is under tension. When the trolley is to be re- 30 placed in contact with the wire the weight is lifted and reseated in the lateral opening of the tube or guide and the parts are then in position for action at the proper time.

For the purpose of readily lifting the 35 weight to reseat it, a cord 13 is attached to the eye-bolt 11 and passed through a sheave 14 suspended by a hanger 15, or otherwise, from the upper part of the tube 5, which cord can be grasped by the conductor so as to lift 40 the weight to position. To insure the quick unseating of the weight when the trolley leaves the line wire, a guard 16 is preferably attached to the tube, preferably about two inches above the slot, as indicated, so that 45 when the trolley pole cord is drawn taut it will engage the guard and thus the eye-bolt will be quickly drawn to the longitudinal slot 8 and the weight permitted to descend. In practice, the guard 16 will preferably be in 50 the form of a rod about $\frac{3}{8}$ of an inch in diameter and 12 inches long. It will prevent the trolley rope from being blown out of proper place when the device is thrown into action.

55 While we have described the tube as constituting the guide, and that is the preferred construction, yet it is to be understood that such is given only as a suitable form of the guide and that changes can be made in the

form of the guide and essential features of 60 the invention retained which will be within the scope of the invention and appended claims.

Having described our invention and set forth its merits, what we claim is:— 65

1. A trolley pole controller, comprising a weight for attachment to a trolley pole cord, and a guide for the weight in its vertical movements, said guide being formed with a laterally disposed seat for sustaining the 70 weight until the weight is moved from its seat by tension on the trolley pole cord, substantially as described.

2. A trolley pole controller, comprising a weight for attachment to a trolley pole cord, 75 a guide for the weight in its vertical movements, a laterally disposed seat on the guide for the weight, and a lateral projection on the weight to engage said seat, substantially as described.

3. A trolley pole controller, comprising a weight for attachment to a trolley pole cord, a tube constituting a guide for the weight, said tube being formed with a longitudinally extending slot in its wall and a laterally disposed slot in communication therewith, and a laterally extending part on the weight working in said longitudinally extending slot and adapted to be seated in the laterally disposed slot, substantially as described. 85

4. A trolley pole controller, comprising a weight for attachment to a trolley pole cord, a tube constituting a guide for the weight and formed with a longitudinally extending slot in its wall and a laterally disposed slot in 95 communication therewith, said lateral slot extending obliquely to the longitudinal slot, and a laterally extending part on the weight working in said longitudinal slot and adapted to be seated in the laterally disposed slot, 100 substantially as described.

5. A trolley pole controller, comprising a weight for attachment to a trolley pole cord, a guide for the weight in its vertical movements, a laterally disposed seat on the guide 105 for the weight, a lateral projection on the weight to engage said seat, and a guard for the trolley pole cord to engage to aid in unseating the weight, substantially as described.

In testimony whereof we affix our signatures in presence of two witnesses.
